UNITED STATES PATENT OFFICE.

ARCHIE TIMMONS, OF ORANGE, TEXAS.

SAFETY HANGER OR DISPLAY DEVICE.

Application filed May 24, 1928. Serial No. 280,367.

This invention relates to a device adapted to display various articles pertaining to the dry-goods business and in fact, merchandise in general.

5 It is aimed to provide a novel construction of hanger which displays the merchandise so that it cannot be removed without the aid of a special key from the rack or supporting element and which cannot be operated to release the merchandise until such key is subsequently unlocked or removed under control of an employee or authorized person.

10 The more specific objects and advantages will be pointed out or become apparent from 15 the description following taken in connection with accompanying drawings illustrating an operative embodiment.

In said drawings:—

Figure 1 is a side elevation of the invention with a key in place to be operated to release the hanger from its support,

20 Figure 2 is a front elevation of the device of Figure 1 with the support shown in section and the key removed,

25 Figure 3 is a sectional view taken on the line 3—3 of Figure 2,

Figure 4 is a sectional view taken on the line 4—4 of Figure 3,

30 Figure 5 is a sectional view taken on the line 5—5 of Figure 2,

Figure 6 is a detail of the key, being shown principally in plan and its cap being shown in horizontal section,

35 Figure 7 is an end elevation of the key looking from the left in Figure 6,

Figure 8 is an end elevation of the cap looking from the right in Figure 6, and

Figure 9 is a sectional view taken on the line 9—9 of Figure 6.

40 In carrying out the invention, two substantially similar metallic plates 10 and 11 are provided which are pivotally connected together for relative movement on a horizontal axis by a rivet or the like as at 11'.

45 At the upper ends, said plates 10 and 11 are provided with hooks 12 adapted to engage part of a rack, or other suitable support conventionally shown at 13 to hang therefrom.

50 The lower end of the plate 10 is provided with a pocket shaped jaw 14 rigid therewith and it has extensions or lugs 15 to which a coacting pocket shaped jaw 16 is pivoted as at 17. The jaws 14 and 16 are adapted to grip an article of merchandise between them 55 and hold it until released through operation of the device by a suitable key in the hands

of an authorized person. Auxiliary sliding jaws 18 are preferably provided in each jaw 14 and 16, having serrated faces at 19 to directly engage the merchandise and which jaws are adapted to slide downwardly to bring the faces 19 closer together and in intimate relation with the merchandise.

55 The auxiliary jaws 18 are held in place and their movement permitted by reason of the provision of set screws 20 fastened to the auxiliary jaws and passing through vertically elongated slots 21 in the jaws 14 and 16.

60 The jaws 14 and 16 are normally held in tight and clamping relation through the engagement of lugs or cams 22 and 23, provided on an upward extension 24 of the jaw 16 and adjacent the lower end of the plate 11, respectively.

65 In order to release the movable jaw 16 for movement on the pivot 17 away from the jaw 14 to receive or release the merchandise, it is necessary that plate 11 be swung on the horizontal axis afforded by rivet 11' so that 70 the lug 23 will disengage the lug 22 in order to permit such movement. The plates 10 and 11 are normally held locked against such relative movement by means of a latch 25 which is pivoted at 26 to the plate 10 and 75 has a hook 27 normally in engagement with a lug 28 on the plate 11. The latch is urged to such position, as specifically shown in Figure 4, by a bowed spring 29 fastened to the plate 10 as at 30 and at its opposite 80 end resting on a lug 31 also fastened to plate 10. The plates 10 and 11 have openings 32 and 33 therethrough, respectively, which in the locked positions of the plates 10 and 11, are slightly disaligned as shown 85 particularly in Figure 2. Such openings have enlargements or notches 34 at their lower portions which are bridged by the aforesaid latch 25 as shown in Figures 2, 3 and 4.

90 A key 35 is used to operate the device and may consist of a rod 36 having a tapered end 37 provided with an offset rib 38 having a notch 39 therein. The key 35 therefore is adapted to have its tapered end 37 inserted 95 through the openings 32 and 33 with its rib 38 riding over and depressing the latch 25 to disengage hook 27 from lug 28 so that plates 10 and 11 may turn on pivot 11'. The insertion of the tapered portion 37 brings the 100 openings 32 and 33 into alignment at which time the hooks 12 are sufficiently spread to 105

enable the device to be lowered or removed from the rack element 13. At the same time, the notch 39 is entered by the latch 25 under the urgency of the spring 29 and hence the key will remain in such position and the plates 10 and 11 cannot be further moved because that portion of the key in the openings 32 and 33 fills them. The key at this time can of course be pushed inwardly but the rod 36 fills the openings 32 and 33 and the key cannot be removed because a cap 39' is locked thereon and will abut the plate 10. Such cap consists generally of a hollow body into which the outer end of the key 35 extends so that resilient fingers 40 at enlargement 41 will snap into a groove 42 provided about the key 35. The fingers 40 are tensioned to move toward each other. The other end of the cap 39 as shown in Figures 6 and 8 has a key hole 43 therethrough through which a key or element may be inserted in order to spread the fingers 40 and thereby release the key 36 which may then be completely withdrawn from the openings 32 and 33 so that the plate 11 may be swung relatively to the plate 10, sufficiently to disengage the lugs 22 and 23 whereupon the article of merchandise may be removed.

30 By reason of the invention, the goods, particularly expensive articles, may be supported or suspended each by a lock or hanger according to the present invention. When a purchaser wishes to purchase the article, he will, by means of the key 35, which is arranged close to the lock, insert the same so as to detach the hanger from the support, and thus he will carry the article with the hanger and key attached to a clerk or authorized person who will by means of a key inserted through the key hole 43, detach cap 39' so that the key may be removed and the article released. The device prevents liability of theft of the goods because the same cannot be folded into a compact form. Also, if desired, the keys 35 may be in the custody of an authorized person, to supply to a purchaser upon request only. In this way, the keys may be traced and the entire system and transaction be under complete surveillance.

40 Various changes may be resorted to provided they fall within the spirit and scope of the invention.

55 I claim as my invention:

1. A device of the class described having plates, means thereon to engage a support, means connecting the plates for relative movement, said plates in their engaged position having openings in disalignment, means to hold the plates in engaged positions, a key insertable into said openings to release said holding means and permit relative movement of the plates to disengage them from the support, said key preventing

movement of the plates sufficiently to release a held article during the presence of the key in said openings.

2. A device of the class described having plates, means thereon to engage a support, means connecting the plates for relative movement, said plates in their engaged position having openings in disalignment, means to hold the plates in engaged positions, a key insertable into said openings to release said holding means and permit relative movement of the plates to disengage them from the support, said key preventing movement of the plates sufficiently to release a held article during the presence of the key in said openings, said holding means being rendered inactive through engagement of the plates with the support.

3. A device of the class described having plates, means thereon to engage a support, means connecting the plates for relative movement, said plates in their engaged position having openings in disalignment, means to hold the plates in engaged positions, a key insertable into said openings to release said holding means and permit relative movement of the plates to disengage them from the support, said key preventing movement of the plates sufficiently to release a held article during the presence of the key in said openings, said holding means being rendered inactive through engagement of the plates with the support.

4. A device of the class described having plates, means thereon to engage a support, means connecting the plates for relative movement, said plates in their engaged position having openings in disalignment, means to hold the plates in engaged positions, a key insertable into said openings to release said holding means and permit relative movement of the plates to disengage them from the support, said key preventing movement of the plates sufficiently to release a held article during the presence of the key in said openings, a releasable cap carried by said key and preventing normal detachment of the key from the lock, said cap having resilient fingers, the key having a groove entered by said fingers, and said cap having a slot accommodating an instrument to separate said fingers to release the key.

5. A device of the class described having plates, means thereon to engage a support, means connecting the plates for relative movement, said plates in their engaged position having openings in disalignment, means to hold the plates in engaged positions, a key insertable into said openings to release said holding means and permit relative movement of the plates to disengage them from the support, said key preventing movement of the plates sufficiently to release a held article during the presence of the key in said openings, a jaw carried by one of the

plates, a jaw pivoted to the first mentioned jaw, engaging lugs between the pivoted jaw and the other plate preventing movement of the pivoted jaw when the plates are locked, 5 said lugs being adapted to disengage through relative movement of the plates after removal of the key.

6. A device of the class described comprising a plurality of pivotally connected plates, said plates having hooks to engage a support, said plates having openings therethrough disaligned in their engaged position, 10

means normally securing the plates in engaged position, and means operable to align said openings to release said hooks from the support and to render said latching means 15 inoperative until the device is reset, said means serving to prevent sufficient movement of the plates to unlocking position during the presence of the key in said openings.

In testimony whereof I affix my signature.

ARCHIE TIMMONS.
